M. CHRISTOPHER ANDREWS, OF LAWRENCE, MASSACHUSETTS.

Letters Patent No. 78,174, dated May 26, 1868.

IMPROVEMENT IN RAILROAD-CAR VENTILATORS.

The Schedule referred to in these Letters Patent and making part of the same.

TO ALL PERSONS TO WHOM THESE PRESENTS MAY COME:

Be it known that I, M. CHRISTOPHER ANDREWS, of Lawrence, in the county of Essex, and State of Massachusetts, have invented a new and useful Mechanism for Operating the Ventilating-Valves or Shutters of Railway-Carriages; and I do hereby declare the same to be fully described in the following specification, and represented in the accompanying drawings, of which—

Figure 1 is a front elevation, and

Figure 2 a horizontal section of it as applied to two ventilating-shutters, one of such shutters being exhibited as open and the other as closed.

The invention is specially intended for use in what are termed "monitor-cars," which, on the sides of their turrets, have openings, provided with shutters or windows hinged to them, so as to be capable of being moved horizontally as a common window-shutter generally is moved on its hinges.

The object of the invention is to either open or close, at once, every other one of the series of shutter on one side of the turret, and, at such time, to maintain the rest of them of such side closed. Each two next adjacent shutters are to be hinged to the turret or frame, so as to swing in opposite directions while being either opened or closed. By this mechanism all the shutters of the range may be closed at once. While the carriage may be in movement in one direction, one half of the shutters are to be opened, so that their external surfaces may be carried against the external air, and it be caused to be deflected from them, so as to induce currents of air to flow from the interior of the carriage through the uncovered shutter-openings. When the carriage may be moved in the opposite direction, these shutters should be closed, and the others be opened.

In figs. 1 and 2 of the drawings, A and B denote two shutters, applied to two next adjacent ventilating-openings C D, and connected to their divisional partition E, by hinges, as shown at a b.

In rear of each opening C D, and on its sill s, is a bent lever, F, arranged to turn transversely on a fulcrum, c. The shorter arm of the said lever is connected with the adjacent shutter, by means of a link, G, jointed both to the lever and to the shutter. The longer arm of the lever makes a right angle with the shorter one, and has a bend, as shown at d. It also has a slot, e, formed through it, and projecting in opposite directions from the bend d, in manner as represented. This slot receives a pin, f, which extends vertically from a long slide-bar, H, disposed underneath both levers. The said levers are arranged so as to project in opposite directions, that is to say, their longer as well as their shorter arms do so project, the same being as shown in figs. 2 and 3.

The bar H is to be disposed in or on the sill or post s of the openings, so as to be capable of being slid endwise back and forth in a rectilinear path or groove, and it is to be so connected with or applied to a lever, I, as to be capable of being moved longitudinally in either direction thereby, such lever being arranged in manner as represented.

The said slide-bar is to extend along in rear of all the shutters of one side of the car, or turret thereof, each of them being connected with the said bar, by appliances, as hereinbefore described, viz, a pin, slotted and bent lever, and connecting-link. It should be observed, however, that the bent levers of each two next adjacent shutters should be arranged so as to project in opposite directions with respect to each other. When the lever I is in a vertical position, all the shutters will be closed, but when such lever is inclined from the vertical in either direction, in its plane of motion, one half of the number of shutters will be open, that is, every other one of the series will be open, and the rest will be closed.

Figure 3 is a horizontal section taken, through a series of the shutters and their openings, and exhibits the arrangement of their levers, when half the number of the shutters are open.

I claim the arrangement of the hinges of each two consecutive shutters of a series thereof, so that such two shutters shall open in opposite directions, as explained, and the combination therewith, of mechanism, as specified, or its equivalent, whereby such shutters may be operated in manner as set forth.

I also claim the combination or mechanism for operating shutters, arranged as specified, such consisting of the slide-bar H, and its operative lever I, or the equivalent thereof, a series of slotted and bent levers, F, and their connecting-links, the whole being arranged together substantially as explained.

I also claim the arrangement of my shutter-operating mechanism with the inner surface of the shutters and the side of the car, whereby such mechanism is all brought within the car, when the shutters are closed.

M. CHRISTOPHER ANDREWS.
